COLLAPSIBLE CHAIR

Herbert Uretsky, Bronx, N. Y.

Application January 12, 1956, Serial No. 39,695

Term of patent 14 years

(Cl. D15—1)

FIG. 1.

FIG. 3.

FIG. 2.

FIG. 4.

Fig. 1 is a front perspective view of the collapsible chair embodying my new design.

Fig. 2 is a rear perspective view,

Fig. 3 is an elevational view of the frame element of the chair in folded position, and

Fig. 4 is a top plan view of the seat element.

I claim:

The ornamental design for a collapsible chair, substantially as shown.
